United States Patent Office

Des. 214,254
Patented May 20, 1969

214,254

PORTABLE LIGHT

Edward P. Cheslock, Chester, Pa., assignor to E. W. Bliss
Company, Canton, Ohio, a corporation of Delaware

Filed July 31, 1968, Ser. No. 12,982

Term of patent 14 years

Int. Cl. D26—04
U.S. Cl. D48—24

FIG. 1

FIG. 2

FIG. 3

The dominant features of my design reside in the portions shown in full lines.

I claim:

The ornamental design for a portable light, substantially as shown and described.
